[57] CLAIM

The ornamental design for a snare drum lug, as shown and described.

DESCRIPTION

FIG. 1 is a perspective view of a snare drum lug showing our new design;

FIG. 2 is a front elevational view thereof;

FIG. 3 is a side elevational view thereof;

FIG. 4 is a perspective view of a second modified embodiment;

FIG. 5 is a front elevational view of FIG. 4;

FIG. 6 is a side elevational view of FIG. 4.

The broken line showing of the snare drum is for illustrative purposes only and forms no part of the claimed design.

The rear of the lug is a concave cylindrical surface without ornamentation.

FIG. 1

FIG. 2

FIG. 3
